FREQUENCY MULTIPLIER

Harry R. Summerhayes, Jr., Schenectady, N. Y.,
assignor to General Electric Company, a corporation of New York

Application September 30, 1943, Serial No. 504,387

3 Claims. (Cl. 250—36)

My invention relates to frequency multipliers and more particularly to apparatus for obtaining frequency multiplication and amplification by utilizing relatively low frequency crystal oscillators.

Crystal oscillators are employed in order to maintain constant frequency; however, at very high frequencies the dimensions of the crystal are so small that the crystal is delicate and difficult to handle. It has, therefore, become the practice of providing frequency multipliers for multiplying the low frequency of the crystal. When high multiplications of frequency are required, it becomes difficult to obtain sufficient energy from the crystal oscillator while at the same time maintaining frequency stability which requires low crystal excitation and limits the available harmonic output necessary for frequency multiplication. Accordingly, it is an object of my invention to provide a frequency multiplier employing a crystal oscillator and including an improved arrangement for maintaining stable operation of the multiplier with relatively low crystal excitation.

It is another object of my invention to provide a frequency multiplier comprising an amplifier and frequency tripler circuits and an improved arrangement for providing a feedback of energy at the desired frequency for increasing the output intensity while maintaining the required low crystal excitation necessary to insure stable operation.

The features of my invention which I believe to be novel are set forth with particularity in the appended claims. My invention itself, however, both as to its organization and method of operation, together with further objects and advantages thereof, may best be understood by reference to the following description taken in connection with the accompanying drawing in which Fig. 1 diagrammatically represents one form of frequency multiplier circuit embodying my invention; Figs. 2 and 3 represent equivalent circuit diagrams of the circuit shown in Fig. 1; and Fig. 4 is a vector diagram illustrating the operation of the circuit.

Referring now to Fig. 1, the frequency multiplier circuit has been illustrated as a harmonic multiplier of a general type well known in the art. An electron discharge device 10 having an anode 11, control electrode or grid 12 and cathode 13 is arranged with a piezoelectric crystal 14 connected between the grid and cathode across the usual grid leak resistor 15. In the output of the device 10 between the anode 11 and the

cathode 13 there are connected a parallel circuit 16 comprising an inductance 17 and a condenser 18, a parallel circuit 20 comprising an inductance 21 and a condenser 22 and a suitable battery or other source of direct current potential 19. The first circuit 16 is tuned to a frequency above but near the natural frequency of the crystal and the second tuned circuit 20 which constitutes the harmonic multiplier is preferably tuned to an odd harmonic of the fundamental frequency. If the circuit 16 were tuned to a frequency very near the natural frequency of the crystal to obtain maximum output, over-excitation and injury or destruction of the crystal might result and stable operation at the required frequency would be impossible. It is for this reason that the circuit 16 is not tuned to provide maximum output but is tuned to a frequency sufficiently above the natural frequency so that the excitation of the crystal is reduced and stable operation insured. The proper adjustment of this type of circuit and the manner in which it operates are well known in the art. The grid leak resistor and the capacities associated therewith, for example, the capacity of the crystal and the grid to cathode capacity of the device 10, are selected so that a negative bias exists on the grid 12 and only positive voltage peaks, cause anode current to flow; the wave form of the anode current is, therefore, rich in harmonics so that the circuit 20 oscillates at the multiple of the fundamental frequency to which it is tuned. It will be understood that the tuning of the circuits 16 and 20 depends not only on the capacities of the condensers 18 and 22 but also on the other capacities which are inherently present in the circuit for example, the capacities of the device 10.

The alternating voltage appearing across the circuit 20 is coupled to the input circuit of an electron discharge device 23 having an anode 24, a control electrode 25 and a cathode 26, the circuit 20 being coupled to the grid 25 through a condenser 21 and a resistance 28. A tuned circuit 30 comprising an inductance 31 and a variable condenser 32 connected in parallel is connected in the output circuit of the device 23 between the anode 24 and the cathode 26 in series with a suitable source of direct current potential such as a battery 33. The circuit 30 is tuned preferably to an odd harmonic of the frequency of the circuit 20, for example, the third harmonic. The time constant of the resistance and capacity combination comprising the resistance 28 and capacitance 27 is chosen so that a nega-

tive bias is maintained on the grid 25 and only the positive peaks of the voltage across the circuit 20 render the device 23 conducting and excite the tuned circuit 30. A utilization device (not shown) may be coupled across the output of the apparatus through a suitable coupling condenser 34. The devices 10 and 23 thus perform the functions of an oscillator, an amplifier and a frequency multiplier. Because of the necessity of maintaining relatively low excitation of the crystal the high frequency energy available at the output of the multiplier must be relatively low provided stable operation is to be obtained. The high frequency output of the tube 23 may be increased by feeding back energy from its output circuit to its input circuit, and I have found that this may be accomplished efficiently with a minimum number of additional circuit elements by employing an inductance 35 connected in series with the control grid 25. A greatly increased high frequency output may be obtained by the circuit when provided with this inductance.

The manner in which the inductance 35 operates to provide the feedback of energy at the frequency of the circuit 30 may readily be understood from the equivalent circuit diagrams of Figs. 2 and 3 and the vector diagram of Fig. 4. In Fig. 2 the impedance of all the components of the circuit of Fig. 1 which are connected between the input of the impedance 35 and ground have been represented by a capacitor 37. Fig. 2 is drawn with reference to the high frequency appearing across the output circuit 30 and the circuits 16 and 20 which are tuned to much lower frequencies present a capacitive reactance at the high frequencies; this assumption neglects the resistance losses which are relatively unimportant. The impedance of the device 10 is also essentially a capacitive reactance in parallel with a high resistance. All these capacitive reactances have been combined and represented by the capacitor 37. The capacity indicated in dotted lines at 38 represents the anode to grid capacity of the device 23 and capacities between the associated leads. The inductance 35 is selected to have a value such that when it is combined in series with the condenser 37 the resultant reactance will be inductive and of the order of one-twentieth of the reactance of the grid to cathode capacity of the device 23 indicated at 39. Furthermore, this combination circuit comprising the inductance and condenser 37 in series shunted by the grid cathode capacity 39 has an effective inductive reactance which may be represented by an inductance 40, as indicated in Fig. 3. Furthermore, since the grid to plate and the grid to cathode capacities of a three-element tube, such as the device 23, are always of the same order of magnitude, the inductive reactance 40 is of the order of one-twentieth the capacitive reactance of the plate to grid capacity 38.

The vector relationships of the voltages and currents in Fig. 3 are indicated in Fig. 4; these vectors are shown with respect to their relative phase relationship but not necessarily with respect to their magnitudes. The vector E_p represents the anode voltage of the device 23. This voltage causes a current represented by the vector I_g to flow through the series circuit including the capacity 38 and the effective inductance 40. The current I_g leads the voltage E_p by 90° because the branch of the anode-cathode impedance consisting of the capacity 38 and inductance 40 in series has an effective capacitive reactance, and

a voltage E_g is developed by the current I_g across the inductance 40 and leads the current by 90° ; the voltage E_g therefore is 180° out of phase with E_p . Since the parallel circuit 30, taking into account the other impedances associated therewith in the anode circuit, is tuned to resonance, it presents a resistive impedance to the voltage E_p , and E_p is, therefore, 180° out of phase with E_g . The voltage E_g and the feedback voltage E_g' are therefore in phase, which is the condition required for regeneration. It will be found that as the effective inductive reactance 40 is increased as by increasing the inductance 35, the feedback of energy from the output to the input of the device 23 is increased until a value of the inductive reactance 40 is reached at which self-oscillation of the circuit occurs. It is, of course, desirable to avoid self-oscillation and for this reason a value of inductive reactance less than that which produces self-oscillation is selected. The increase in output produced by a value of inductive reactance below the value for self-oscillation is still very substantial and makes it possible to operate the circuit with the relatively low excitation of the crystal which is necessary to insure frequency stability. Greatly increased output at the high harmonic frequency may thus be obtained.

It will be evident that my invention provides a structurally simple and effective frequency multiplying circuit with a minimum number of circuit components. By proper selection of the feedback impedance 35, high efficiency and stability are attained together with amplification without the necessity of increasing the crystal excitation. By way of illustration only, and not by way of limitation, there are listed below values of circuit constants which have been found to be suitable for the circuit of Fig. 1 when employed in a particular frequency multiplier in which the harmonic circuits 20 and 30 were tuned to the third harmonic of the fundamental frequency and the frequency of the circuit 20, respectively. The devices 10 and 23 were the two sections of a Type 6N7 tube. Condensers 18 and 22 were 5 to 25 μ fd. air trimmer capacitors set at approximately 10 μ fd. each. A satisfactory value of the inductance 35 was found to be approximately 0.4 microhenry. The crystal oscillator frequency was 7.372 megacycles. The direct current potential of the sources 19 and 33 was 250 volts. The values of the remaining constants were as follows:

Resistor 15	50,000 ohms
Resistor 28	100,000 ohms
Condenser 27	.0001 μ fd.
Condenser 32	5 to 25 μ fd. air trimmer
Condenser 34	.0001 μ fd.
Inductance 17	11 μ hy.
Inductance 21	1.2 μ hy.
Inductance 31	5 turns $\frac{3}{4}$ " dia., 1" long 80 mil wire.

Although I have illustrated one embodiment of my invention, other modifications will readily occur to those skilled in the art. I do not, therefore, desire my invention to be limited to the particular circuit illustrated and described and I intend in the appended claims to cover all modifications which fall within the spirit and scope of my invention.

What I claim as new and desire to secure by Letters Patent of the United States is:

1. A frequency multiplying apparatus comprising an electron discharge device having a cathode and an anode and a control electrode,

an input circuit tuned to a fundamental frequency and connected between said cathode and said control electrode, an output circuit tuned to a harmonic of the fundamental frequency and connected between said anode and said cathode, said input circuit being capacitive at said harmonic frequency, means providing a negative bias for said control electrode whereby only positive wave peaks at said fundamental frequency render said device conducting, and an inductance connected in series between said control electrode and said tuned input circuit for providing regenerative feedback of energy at said harmonic frequency.

2. A frequency multiplying apparatus comprising a crystal oscillator, a circuit in the output of said oscillator tuned to a predetermined frequency, an amplifier comprising an electron discharge device having an anode and a cathode and a control electrode, the control electrode to cathode circuit of said amplifier being connected to include said tuned circuit, an output circuit for said amplifier connected between said anode and said cathode and tuned to a harmonic of the frequency of said first mentioned tuned circuit, the input circuit of said amplifier being capacitive at the frequency to which the output circuit thereof is tuned, means providing a negative bias for said control electrode whereby only positive wave peaks at the frequency of said first mentioned tuned circuit render said device conducting, and an inductance connected in

series between said control electrode and said first tuned circuit for providing a regenerative feedback of energy at said harmonic frequency.

3. A frequency multiplying apparatus comprising a crystal oscillator including an electron discharge device having a piezoelectric crystal connected in the input circuit thereof, and a first circuit tuned to the fundamental frequency of the crystal connected in the output circuit thereof, 10 a second tuned circuit connected in the output of said device and tuned to a harmonic of said fundamental frequency, an amplifier comprising an electron discharge device having an anode and a cathode and a control electrode, 15 the control electrode to cathode circuit of said amplifier being connected to include said second tuned circuit, an output circuit for said amplifier connected between said anode and said cathode and tuned to a harmonic of the frequency of 20 said second tuned circuit, said second tuned circuit being capacitive at the frequency to which said output circuit is tuned, means providing a negative bias for said control electrode whereby only positive wave peaks at the frequency of said 25 second tuned circuit render said device conducting, and an inductance connected in series between said control electrode and said second tuned circuit for providing a regenerative feedback of energy at the frequency of said output 30 circuit.
